(57) CLAIM

We claim the ornamental design for an embedded cellular modem, as shown and described.

DESCRIPTION

FIG. 1 is a downward perspective view of an embedded cellular modem, according to an embodiment of the invention;

FIG. 2 is an upward perspective view of the embedded cellular modem of FIG. 1;

FIG. 3 is a top plan view of the embedded cellular modem of FIG. 1;

FIG. 4 is a bottom plan view of the embedded cellular modem of FIG. 1;

FIG. 5 is a front elevational view of the embedded cellular modem of FIG. 1;

FIG. 6 is a rear elevational view of the embedded cellular modem of FIG. 1;

FIG. 7 is a right-side, elevational view of the embedded cellular modem of FIG. 1; and,

FIG. 8 is a left-side, elevational view of the embedded cellular modem of FIG. 1.

Broken lines and entirely unshaded portions contained within broken lines are not claimed.
